W. E. PETTENGILL

WRAPPING WIRE

Filed July 27, 1926

UNITED STATES PATENT OFFICE.

WALTER E. PETTENGILL, OF EAST PROVIDENCE, RHODE ISLAND.

WRAPPING WIRE.

Application filed July 27, 1926. Serial No. 125,296.

This invention relates to a machine for wrapping a covering about a strand of wire; and the object of this invention is to provide a wrapping head through which the wire 5 passes, which has a presser member so mounted that it will exert an even pressure on the covered wire along its entire pressing face.

A further object of the invention is to 10 provide a construction in which the springs for exerting pressure on the presser member may be of such form or shape that they will not be easily broken.

A still further object of the invention is 15 to provide a construction in which the springs, presser member, and other parts may be easily replaced and adjusted.

With these and other objects in view, the 20 invention consists of certain novel features of construction, as will be more fully described, and particularly pointed out in the appended claims.

In the accompanying drawings:

Figure 1 is a side elevation illustrating 25 the wrapping head, yarn and flyer in their relative working positions.

Figure 2 is a perspective view of the wrapping head showing a portion cut away for the leading of the covering yarn to the wire.

Figure 3 is a perspective view of the opposite side of the wrapping head with the presser member removed.

Figure 4 is a perspective view of the presser member, its pivot pin, springs and rod 30 for mounting it in the body of the wrapping head.

Figure 5 is a perspective view of the presser member.

Figure 6 is a sectional side elevation showing 40 the position of the presser member on the body of the wrapping head and also showing a set screw for holding the rod for mounting the springs in different positions of adjustment.

Figure 7 is a sectional elevation at right angles to that shown in Figure 6 showing the set screws for retaining the springs in both the pivot pin for the presser member and the mounting rod.

Figure 8 is a central sectional elevation 50 of the presser member illustrating the bushing mounted therein.

It is found in practice in the construction of wrapping heads having a presser member, desirable to so mount the presser member that there will be a substantially even pressure along its face; and to accomplish this result I have pivotally mounted the presser on an axis at right angles to the travel of the wire to be covered so that it 55 may swing freely on its pivot to evenly distribute the pressure applied to the pivot pin by means of a pair of springs for swinging the pivot towards the wire.

It is also desirable to bush the opening in 60 the wrapping head with a material harder than that of the body of the head so as to better resist the wear of the wire and its covering passing therethrough and also by this use of bushings having various sized 65 openings to regulate the size of the wire-guiding opening to different sized wires; and the following is a detailed description of one embodiment of this invention illustrating one means by which these 70 advantageous results may be obtained:—

With reference to the drawings, 10 designates a package of yarn or of suitable insulating material to be wrapped about the wire 11 which is passed through the center 80 of the package.

On the package spindle there is mounted a wrapping head 12 having an opening 13 therein through which the wire to be covered passes to be reeled on a drum 14 which 85 may be located at any suitable place and driven by means (not shown).

A suitable bushing 15 of a material harder than the body is inserted and removably held by any suitable means in this opening 90 13 to resist the wear of the wire and covering passing therethrough. It is understood that bushings having a guide opening suitable to the wire used will be utilized and that these bushings may be varied at will 95 without removing the head. The body of the head is cut away as at 16 to permit the entrance of the strands of yarn 17 which are led through the pigtail guide 18 of the flyer 19 in passing from the yarn package 100 to the wire. It is understood that the package, flyer and head are suitably rotated about the wire by means (not shown) to wrap the covering thereon.

As the covering is wrapped on the wire, it is desirable to press or iron the covering, and to accomplish this result the body of the head and the bushing therein are cut away 5 as at 20 and a presser member or block 21 is rotatably mounted on a pivot 22 which is carried by springs 23 and pressed into engagement with the wire by means of the springs.

10 The springs 23 are mounted in openings in the rod 24 which is rotatably mounted in the opening 25 in the body of the wrapping head. These springs may be adjusted to the desired tension by rotating the rod 24 in its 15 opening or bearing 25 and when in its desired position set screws 26 are manipulated to engage the rod and hold the same in this desired position of adjustment.

The springs 23 are held in their openings 20 in the mounting rod 24 and in pivot pin 22 by means of suitable set screws 27 and 28, respectively, by means of which any desired adjustment may be obtained. In order that the yarn may be initially manually wrapped 25 about the wire before mechanical rotation of the head, a slot 28 is provided connecting the openings 16 and 20 through which yarn may be manually led and wrapped about the wire beneath the presser before the machine is 30 started, which initial turns are sufficient to start the wrapping of the yarn on the wire.

I have illustrated the opening 16 as cut on an angle substantially that at which the yarn leads to the wire when the wrapping takes 35 place by rotation of the yarn, flyer and head in one direction, but it is understood that there are right hand and left hand wrappings placed on the wire and the angle of the opening 16 may be opposite disposed in a 40 wrapping head which is designed to be rotated in the opposite direction.

From the foregoing it will be seen that I have provided a wrapping head which is simple in construction, one in which the 45 springs have no sharp angles or bends to be easily broken and one in which the pressure of the presser member is such that an even distribution of pressure along its ironing face on the yarn is provided.

50 The foregoing description is directed solely towards the construction illustrated, but I desire it to be understood that I reserve the privilege of resorting to all the mechanical changes to which the device is susceptible, the invention being defined and limited only by the terms of the appended 55 claims.

I claim:

1. In a wrapping machine, a wrapping 60 head comprising a body through which the wire passes, a presser member, and spring means bodily carrying said member and yieldingly moving it into engagement with said wire after it has been covered.

65 2. In a wire wrapping machine, a wrap-

ping head comprising a body through which the wire passes, a presser member, springs bodily carrying said member and moving it towards said wire, and means for adjusting the tension of said springs to vary the pressure on the wire.

3. In a wire wrapping machine, a wrapping head comprising a body through which the wire passes, a presser member, a pair of springs carrying said presser member and a 75 rod rotatably mounted in said body and carrying said springs, and means for holding said rod in different positions of rotation to simultaneously adjust the tension on both springs for swinging the presser towards the 80 wire.

4. In a wire wrapping machine, a wrapping head comprising a body through which the wire passes, and a presser member having a plurality of engaging faces pivotally 85 mounted to have anyone of its faces moved into working position.

5. In a wire wrapping machine, a wrapping head comprising a body through which the wire passes, a presser member having a 90 plurality of working faces, means for mounting said member to permit of automatic adjustment to evenly distribute the pressure along its face and to permit it to be moved to change its working face.

6. In a wire wrapping machine, a wrapping head comprising a body through which the wire passes, a pivot pin, a presser member having a plurality of working faces pivotally mounted on said pin, and means for 100 swinging said pin and member yieldingly into engagement with said wire after being covered.

7. In a wire wrapping machine, a wrapping head comprising a body having an 105 axially disposed opening, a bushing of a material harder than the body in said opening through which the wire passes, a rod having spring wire openings therein rotatably mounted in said body, a spring in 110 each of the rod openings, a pivot pin carried by said springs, a presser block pivotally mounted on said pin for engaging the wire after being covered, and a set screw in said body engaging said rod to retain it in different positions of adjustment for varying the tension on the springs and the pressure 115 on the covered wire.

8. In a wire wrapping machine, a wrapping head having a body with an axial opening 120 therein, said body being cut away on its opposite sides in staggered relation to the depth of said opening and having a slot joining said cut-away portions to permit the initial wrapping of yarn on the wire.

9. In a wire wrapping machine, a wire 125 wrapping head having a body with an axially disposed opening, said body being cut away at suitable parts to said axial opening and a removable bushing of a material 130

harder than the body in said opening and cut away at points to register with the cut away part of said body.

10. In a wire wrapping machine, a wire wrapping head having a body with an axially disposed opening, said body being cut away to said axial opening at a suitable part, a presser working through said cut

away part and a bushing positioned to have its upper end substantially flush with the upper end of the body and having a portion cut away to register with the cut away part of the body.

In testimony whereof I affix my signature.

WALTER E. PETTENGILL.
